UNITED STATES PATENT OFFICE

WILLIAM H. MORRIS, OF DAYTON, OHIO; LILLIA A. MORRIS ADMINISTRATRIX OF
SAID WILLIAM H. MORRIS, DECEASED.

FLORAL RACK.

1,185,525.

Specification of Letters Patent. Patented May 30, 1916.

Application filed October 17, 1914. Serial No. 867,202.

To all whom it may concern:

Be it known that I, WILLIAM H. MORRIS, a citizen of the United States, residing at Dayton, in the county of Montgomery and 5 State of Ohio, have invented certain new and useful Improvements in Floral Racks; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to improvements in racks or brackets and more specifically to a special form of rack for supporting flowers and floral emblems around a burial casket during funeral services.

20 The object of the said invention is to provide a neat and suitable rack or bracket a suitable number of which may be arranged around the casket to support the floral designs, etc., free from contact with the body in 25 the casket. The effect is to surround the casket with a continuous inclosure of flowers which, at the same time, does not conceal the body within the casket. In a word, the floral offerings inclose the remains in a wreath as 30 it were and enable them to be viewed. In funeral services much awkwardness and inconvenience is experienced in arranging and disposing of the floral offerings. Owing to the lack of a suitable or appropriate place to 35 put them, they are often placed on tables, shelves, pianos, or elsewhere, away from the casket, or else they are placed on the remains in the casket. Neither of these is a desirable way of arranging floral offerings on such 40 occasions. The present means provides a more desirable and altogether preferable way of displaying the floral offerings.

45 Preceding a more detailed description of my improved floral display rack, reference is made to the accompanying drawings of which—

50 Figure 1 is a perspective view of my improved floral bracket; Fig. 2 is a sectional view showing the bracket or rack in position on a casket.

55 In a detailed description of my improvement, the same reference characters indicate the same parts in the drawings and specification.

55 The casket 11 may be of any of the well

known forms of burial caskets from the most inexpensive to the more costly. The bracket or rack may be arranged on the lid of the casket in case the lid should be hinged. In the drawings, I have shown a casket having 60 a removable lid or cover with the bracket supported on one of the sides thereof, it being understood that similar brackets are arranged on the opposite side and at the head and foot of the casket so that the body shall 65 be surrounded by a floral frame. It is essential that the supporting rack shall be of minimum weight, therefore, it consists of relatively thin metal bars with sufficient strength only to properly support the flowers, etc. 70 The said bracket comprises flat end members or bars 1—1 the ends 6—6 of which are formed into hooks which delicately engage the inner side of the casket and extend outwardly. The opposite ends are turned to 75 provide right angle portions 10—10. Distance bars 2—2 of a like thin flat character are rigidly united to the end bars 1—1 by means of thumb screws 3, or in any suitable manner. These bars 2—2 have longitudinal 80 slots 5 with binding screws 4 passing therethrough. This manner of connecting the lateral bars 2—2 provides for a suitable adjustment of the rack. For example, when said rack is not in use, it may be reduced to 85 a narrow compass by loosening the screws 4 and moving the end bars 1—1 toward each other as far as the lateral bars 2—2 will permit and then retightening said screws 4. The outer ends of the ends 10—10 of the bars 90 1—1 have connected to them supporting arms 7—7 which are adjustable longitudinally with reference to the surface which they engage for example, the outer side of the casket 11 or the outer side of the casket 95 cover, depending upon where the bracket or rack is placed. The arms 7—7 are provided with longitudinal slots 8 through which the thumb screws 9 pass and by means of which said arms 7—7 are connected to the end bars 100 11 in a manner permitting of adjustment. The ends of said arms suitably formed to securely engage the side of the casket and owing to such formation of said ends the possibility of marring the surface of the casket 105 is obviated. Moreover, the service for which the device is intended is such that enables the flower-receiving part thereof to be open or to consist of bars, and thus a degree of requisite delicacy of structure is observed. 110

Having described my invention, I claim.

A collapsible flower rack adapted to be supported wholly upon a burial casket and consisting of end bars each terminating at 5 one end in a downwardly extended pointed hook adapted to extend over the edge of the casket and engage the inner side thereof, straight supporting arms having longitudinal slots in the outer portions thereof, clamp- 10 ing bolts penetrating the outer ends of said end bars and the longitudinal slots in said supporting arms and whereby the inclinations of said end bars relative to the casket are adjusted, said supporting arms having 15 their free ends pointed to engage the outer side of the casket, horizontal bars connecting

said end bars and having longitudinal overlapping slots, and clamping bolts penetrating said slots whereby the width of the flower rack is adjusted, said horizontal bars 20 being united to the end bars near the outer and inner ends of said end bars whereby an open and comparatively light rack is provided for supporting floral offerings, substantially as specified.

In testimony whereof I affix my signature, in presence of two witnesses.

WILLIAM H. MORRIS.
